(57) **CLAIM**

The ornamental design for a heated folding chair, as shown and described.

DESCRIPTION

FIG. 1 illustrates a perspective view of the claimed design for a heated folding chair;

FIG. 2 illustrates a front view thereof;

FIG. 3 illustrates a back view thereof;

FIG. 4 illustrates a first side view thereof;

FIG. 5 illustrates a second side view thereof;

FIG. 6 illustrates a top view thereof; and,

FIG. 7 illustrates a bottom view thereof.

The longer dashed lines showing the chair frame are for the purpose of depicting environment and form no part of the claimed design. The shorter dashed lines shown on the chair fabric represent stitching and form no part thereof.
